WALTER J. PASINSKI, OF DETROIT, MICHIGAN, ASSIGNOR TO BURROUGHS ADDING MACHINE COMPANY, OF DETROIT, MICHIGAN, A CORPORATION OF MICHIGAN.

FULL-STROKE MECHANISM AND OVERTHROW-PREVENTER FOR ADDING-MACHINES.

1,229,508.

Specification of Letters Patent. Patented June 12, 1917.

Application filed July 30, 1915. Serial No. 42,697.

To all whom it may concern:

Be it known that I, WALTER J. PASINSKI, a citizen of the United States, residing at Detroit, in the county of Wayne and State 5 of Michigan, have invented certain new and useful Improvements in Full-Stroke Mechanism and Overthrow-Preventers for Adding-Machines, of which the following is a specification.

Though not limited thereto this invention has been devised for application to an adding machine of the general type of that disclosed in my prior Patent 1,023,168 issued April 16, 1912 (see also Patent 1,016,501 issued February 6, 1912, upon the invention of Allen A. Horton) and this present invention relates to control of the handle which effects the forward turning to zero of the registering wheels when the machine is to be made ready for a new series of operations. Violent use of this handle may be practised to the injury of the registering mechanism or may, through the rebound of arresting devices, result in over-rotation of 25 the wheels so that instead of being left showing zeros one or more of them may exhibit digits which condition if observed necessitates a second operation of the handle and if not observed leads to erroneous registration 30 in subsequent operations of the machine. Erroneous results may also be brought about by short-stroking the handle. Thus, through ignorance or inexperience, or other cause, or with wilful intent to misoperate the machine, the handle, after having been pulled forward, may be let return part way and then pulled forward again.

The object of the present invention is to effectively guard against any such damaging or objectionable effects as above referred to and I accomplish my object through employment of one and the same devices for checking excessive speed of movement of the zeroizing handle and for compelling a full stroke thereof. I am aware that these things separately considered are not novel but I believe it to be new with me to combine these functions in one and the same device or set of devices.

In the drawings which accompany and form a part of this specification, Figure 1 represents in left side elevation a portion of an adding machine of the type above referred to, said machine being equipped with 55 means for carrying out my invention and all

parts being shown at normal; Fig. 2 is a fragmentary side elevation of some of the same parts but illustrates a condition during forward movement of the zeroizing handle at normal speed; Fig. 3 is a similar view illustrating the effect of driving forward said handle at excessive speed; Fig. 4 is a similar view illustrating the full stroke function of the same means.

As above stated the machine which I have chosen for purposes of detailing a specific embodiment of my invention, is of the general type of that illustrated in my aforesaid prior patent. The machine illustrated is in fact one of a somewhat later construction but it is unnecessary to describe the particulars of the machine proper, either with respect to its adding functions or zeroizing action. Gears which are associated with the numeral wheels at the front of the machine are indicated in Fig. 1, the reference numeral 2 designating one of such gears. Other gearing appears in this figure through the medium of which the wheels are driven from the keys 3. As in the case of the machine illustrated in my aforesaid prior patent, the driving means for the zeroizing mechanism comprises a rock shaft 4, a crank arm 5 secured thereto, and spring-connected links 6 by which said crank arm is coupled to a crank arm 7 fastened to the handle shaft 8. The handle itself is designated by the numeral 9 and is designed as usual to be locked to said shaft. The above described driving devices are as usual held rearward normally by a spring 10.

Referring now to the devices applied to said driving means in the carrying out of my invention, there is formed integral with the crank arm 7 a segmental plate 11 having along its upper edge a series of rack teeth 12. These are somewhat widely spaced apart and their front faces are abrupt or substantially radial to the shaft 8, whereas their rear faces are inclined. Rearwardly beyond this series of teeth there is a deep notch 13 in said segmental plate, the bottom of this notch merging into the back of the rearmost tooth 12.

A pawl 14 is centrally pivoted to a side plate of the machine in the same general vertical plane which the crank arm and segmental plate occupy. This pawl is of angular form and comprises a forwardly and a rearwardly extending arm. A spring 15

applied to the rearwardly extending arm normally holds it elevated and holds the forwardly extending arm correspondingly depressed. In the normal rearward position 5 of the segment 11 it stands rearward of this forward arm of the pawl, as illustrated in Fig. 1. The position of the pawl as yieldingly maintained by the spring 15 is such that the lower corner of the forward arm 10 of the pawl is directly in the path of movement of the teeth 12 of said segment, and the disposition of the pawl end is such that this lower corner thereof functions as a cam nose in coöperation with said teeth as 15 the handle 9 is pulled forward. The dimensions of the pawl and the spacing of the teeth are such that the pawl spans the distance between three of the teeth. The camming action between the front end of the 20 pawl and a forward tooth of the rack results in rocking the pawl in opposition to the spring 15 and thereby moving the end of the rear arm of the pawl toward the rack. In normal speed of movement of the zeroizing 25 handle the effect is that illustrated in Fig. 2, said rear end of the body simply approaching the rack without interposing itself in the path of a tooth thereof. The end edge of this rear arm of the pawl is abrupt in 30 character, for the purpose of blocking the handle in its forward movement under excessive speed. The effect under such conditions is illustrated in Fig. 3. Excessive speed of forward movement of the zeroizing 35 handle will throw the forward arm of the pawl off the forward rack tooth and thereby the rear end of the pawl will be thrown into the path of the abrupt forward face of a rear tooth of the rack.

40 In the above described manner the machine will be protected against violent application of force to drive the zeroizing handle forward, and over-throw effects will be guarded against.

45 Passing now to the matter of compelling a full rearward stroke of the zeroizing handle, I utilize the same pawl 14 for this purpose, which functions as above described to regulate the speed of movement of the 50 handle. The deep notch 13, before mentioned, comes into play in connection with compelling full strokes. The spring 15 is constantly tending to hold the pawl in the position illustrated in Fig. 1 and when the 55 handle has been pulled all the way forward, the rearmost tooth 12 will have passed by the front end of the pawl. Then the deep notch 13 comes under the pawl and permits it to be swung to its normal position by the 60 spring 15. Then when the handle moves rearward the inclined backs of the rack teeth 12 will successively wipe past the pawl, as illustrated in Fig. 4. The spring 15 being centralized with reference to the pivot of 65 the pawl will in this wiping operation be

swung upwardly and distended above the center line, or line running from the fixed supporting spring stud to the pawl pivot stud. The spring will therefore throw the pawl in front of the rack teeth as the latter 70 wipe past the point of the pawl, so that any reverse movement of the handle will be obstructed by encounter of the abrupt front edge or face of a tooth against the end edge of the pawl, until the handle has partaken 75 of its full rearward stroke and the last or foremost tooth as passed by the pawl. Then of course the pawl reassumes its normal position.

I am of course aware that full stroke 80 pawls having the above described tumbling action are well known, and I am likewise aware that a speed controlling action of the character of that above described is old, and I do not herein claim either of these things 85 *per se*, but only the combination whereby, through the same set of devices I am enabled to obtain both results.

I claim:

1. The combination with a reciprocating 90 handle, of means checking its movement when driven beyond desired speed, and co-operating means for compelling full movement in one direction before reversing.

2. The combination with a movable handle, of a rack and pawl one of which is carried by the handle and the other of which is fixed, the pawl being pivoted intermediate 95 its ends and spring-held in camming relation to the teeth of the rack at one end and adapted under momentum to engage the teeth at its other end and thereby arrest the motion of the handle, together with provisions for compelling a full stroke of the handle.

3. The combination with a movable handle, of a rack and pawl one of which is carried by the handle and the other of which is fixed, the pawl being pivoted intermediate 100 its ends and spring-held in camming relation to the teeth of the rack at one end and adapted under momentum to engage the teeth at its other end and thereby arrest the motion of the handle together with means for tumbling the pawl to constitute it a means for compelling a full stroke of the handle.

4. The combination with a movable handle, of a rack and pawl one of which is carried by the handle and the other of which is fixed, the pawl being pivoted intermediate 105 its ends and spring-held in camming relation to the teeth of the rack at one end and adapted under momentum to engage the teeth at its other end and thereby arrest the motion of the handle, the rack having a deep terminal notch for the first mentioned end of the 110 pawl to enter as the handle completes a stroke in one direction, said pawl end then serving, through coaction with the rack-teeth, to compel a full stroke of the handle 115 in the opposite direction.

5. The combination with an oscillating handle, of a segmental rack carried thereby and having widely spaced teeth with forward facing abrupt edges, said rack having
5 a deep notch beyond the series of teeth; a pivoted pawl with a cam-nose on one side of its pivot and a relatively abrupt nose on the other side of its pivot; and a spring holding the cam-nose normally in the path of the
10 rack-teeth, the abrupt nose adapted under momentum to engage the abrupt edges of the rack teeth and thereby arrest the handle, and the cam-nose adapted to enter the deep notch of the rack as the handle completes its
15 initial stroke and to then coöperate with the rack-teeth to compel a complete return stroke of the handle.

6. The combination with an oscillating handle, of a segmental rack carried thereby
20 and having widely spaced teeth with for-

ward facing abrupt edges, said rack having a deep notch beyond the series of teeth; a pivoted pawl with a cam-nose on one side of its pivot and a relatively abrupt nose on the other side of its pivot; and a spring holding 25 the cam-nose normally in the path of the rack-teeth, the abrupt nose adapted under momentum to engage the abrupt edges of the rack teeth and thereby arrest the handle, and the cam-nose adapted to enter the deep 30 notch of the rack as the handle completes its initial stroke and to then coöperate with the rack-teeth to compel a complete return stroke of the handle, the said spring crossing the line between its fixed point of attachment 35 and the pawl-pivot.
